Edward D. Green,
Inventor:
By Charles O. Shurley Atty.

Patented Nov. 17, 1925.

UNITED STATES PATENT OFFICE.

EDWARD D. GREEN, OF CHICAGO, ILLINOIS.

COMPOUND TURBINE BLOWER.

Application filed August 18, 1924. Serial No. 732,601.

To all whom it may concern:

Be it known that I, EDWARD D. GREEN, a citizen of the United States, and a resident of Chicago, Cook County, and State of Illinois, have invented certain new and useful Improvements in Compound Turbine Blowers, of which the following is declared to be a full, clear, and exact description.

This invention relates to compound turbine blowers, and is in the nature of an improvement upon the compound turbine blower shown and described in my prior Patent No. 1,418,704 issued June 6, 1922.

Among the objects of the present invention are to increase the efficiency of blowers of the type disclosed in my former patent, to simplify and reduce the cost of construction thereof, and to otherwise improve thereon. With these and other objects and advantages in view, this invention consists in the several novel features of construction, arrangement and combination of parts, hereinafter fully set forth and claimed.

The invention is clearly illustrated in the accompanying drawing, in which:—

Fig. 1 is a view, partly in side elevation and partly in central vertical section of a compound turbine blower illustrating the preferred embodiment of the present invention; Fig. 2 is a vertical, cross section thereof, taken on the broken line 2—2 of Fig. 1, and Fig. 3 is a vertical, cross section taken on line 3—3 of Fig. 1.

Referring to said drawing, which illustrates one embodiment of the invention, the reference character 10 designates the casing of the blower, which may comprise two substantially circular heads or end walls, 12, 13 and a cylindrical wall 14 bolted or riveted to the heads or end walls 12, 13. The head 12 has a centrally located air inlet opening 14^a, and the wall 14 near the head 13 has a tangential discharge opening 15. Journaled in bearing brackets 16, is the drive shaft 17, which is axially disposed with respect to the casing and has fans 18, 18^a, 18^b secured to it, which fans may be constructed substantially like the fans disclosed in my above identified prior patent. Briefly each fan 18, comprises a hub 19 rigidly secured to the shaft 17, a disc or plate 20 secured to the hub 19, an annular ring or plate 21 spaced away from the disc or plate 20, and blades or vanes 22 secured to and connecting the disc 20 and ring 21. As in my prior patent the tips 23

of the blades or vanes 22 may be twisted or bent back along oblique lines, whereby the air, in leaving the fans, may flow in an outward and lateral direction. The inner edge of the ring or annular plate 21 of the fan 60 defines the air inlet opening 18^c of the fan, which opening is approximately of the same diameter as the inlet opening 14^a, of the casing. The circular plates 20, 21, and blades 22 form air passages through the fan, the inlet openings of which are at the inner edges of the blades, and the discharge openings at the outer edges thereof. Air enters each fan through the inlet opening 18^c, is thrown outward through the passages between the blades thereof and discharges outwardly and in a lateral direction from the periphery of the fan into an annular channel or passage 24, located between the periphery of the fan and the cylindrical wall 75 14 of the casing. All of the fans shown are substantially of the same construction as the one just described, and it is to be understood that such description applies to all of them.

The fans are spaced apart upon the shaft, 80 and between said fans are annular partition walls 25, which are secured to the cylindrical wall 14, as for instance by bolts or rivets 26, that extend through said cylindrical wall and through lugs or angle brackets 27 welded or otherwise fastened to the annular partition walls 25. The fan 18 is placed adjacent the head 12 of the casing, and beyond the fan 18^b is an annular partition wall 28, similar to the walls 25 and 85 secured to the case in like manner. The head 12, partition walls 25, 25, 28 and cylindrical wall 14 form chambers between them, in one side of each of which, is one of the fans, and between each fan and partition 90 wall 25, or 28 is a space which is divided into a plurality of air passages 29, by stationary vanes or blades 30, 31. Said stationary vanes or blades have angular outer ends and extend tangentially from places 95 somewhat distant from the cylindrical wall 14 toward the annular inlet openings 25^a of the partitions 25, 28, the stationary vanes or blades 30 extending to said openings, and the stationary vanes or blades 31, extending 100 only part way, preferably about half way so as to leave comparatively wide ports or openings between the inner edges of the stationary vanes or blades 30, whereby there 105 may be unrestricted openings for the dis- 110

- 2
- charge of air from the air passages between the fans and partition walls, into the inlet opening of an adjacent fan. The stationary vanes or blades 30, 31 may be cast with the 5 partition walls 25, 28 if desired, and they may extend to within a slight distance of an associated fan disc or plate 20. The outer end portions of the edges 32 of said stationary vanes or blades may project close 10 to said fan discs and may be machined to fit fairly close to said discs. In order to obtain the desired results, the outer ends of the vanes or blades must be spaced sufficiently distant from the cylindrical wall of 15 the casing to leave an annular free and unobstructed air passage to permit of the unobstructed flow of the air in a circular path, because if the space between the cylindrical wall and ends of the vanes is not sufficient 20 to permit of the free and unobstructed circular movement of the air the efficiency of the blower is immediately impaired. The cross sectional area of the annular air passage 24 is therefore made relatively large, 25 the distance between the ends of the stationary vanes or blades 30 and the cylindrical wall 14, being not less than that between the periphery of the fan and said wall.
30. The space between the partition wall 28 and head 13 comprises a chamber 33 for the accumulated air, and the discharge conduit 34 leads away from said chamber 33.
- The shaft 17 may be motor driven or it 35 may be belted to a suitable drive pulley as desired.
- In the operation of the present blower, air is taken into the casing through the inlet opening 14^a in the head 12 and enters 40 the spaces between the fan blades 22 of the fan 18, where it is thrown outwardly at great velocity and is deflected toward and into the annular air passage 24 by the tips 45 of the blades 22. The air moves at a high velocity through the annular air passage in a circular direction and thereafter flows into the air passages 29 between the stationary vanes or blades 30, 31 which direct it to the first opening 25^a, through 50 which it flows and enters the spaces between the blades of the second fan 18^a, which throws it outward at an increased velocity and it enters the passages between the stationary vanes or blades of the second set of 55 passages 29, and thence into the third fan 18^b, its velocity being increased, progressively as it is acted on by each succeeding fan, finally entering the chamber 33 and passing out through the discharge conduit 34.

60 By reason of the stationary vanes or blades 30, 31, the tendency for the air to swirl and eddy in the air spaces between the fans and partitions, is eliminated and 65 greater efficiency is obtained. Furthermore

70 by reason of the contracting spaces in the air passages 29, the velocity of the air is increased when passing therethrough. The short vanes permit the use of a greater number of vanes without unnecessarily reducing the size of the discharge ends of said passages, and I have found this of particular advantage in producing a highly efficient blower of this type. The rounded end walls 75 of the air chambers of the construction is reduced, the weight, and number of parts are reduced, the parts may be assembled by less skilled workmen, and less machine work is necessary without sacrificing efficiency in 80 any manner.

85 More or less variation of the exact details of construction is possible without departing from the spirit of this invention; I desire, therefore, not to limit myself to the exact form of the construction shown and described, but intend in the following claims, to point out all of the invention disclosed herein.

I claim as new, and desire to secure by Letters Patent:

90 1. A compound turbine blower comprising 95 a cylindrical casing having an air inlet opening and an air discharge opening, and having a plurality of chambers separated by partition walls and connected by 100 openings through said partition walls, a drive shaft, and fans mounted thereon, the fan blades of which have end tips that are inclined with respect to the remainder of the 105 blades, there being one fan in each of said chambers, and located at one side thereof to leave a space at the other side thereof, the space between each fan and a partition wall being divided into an outer free and unobstructed annular air passage of relatively 110 large cross sectional area, into which the air is deflected by said end tips of the fan blades, and a plurality of air passages leading from said annular air passage to the opening in the partition wall.

115 2. A compound turbine blower comprising 120 a cylindrical casing having an air inlet opening and an air discharge opening and having a plurality of chambers separated by partition walls and connected by 125 openings through said partition walls, a drive shaft and fans mounted thereon, the fan blades of which have end tips that are inclined with respect to the remainder of the fan blades, there being one fan in each of 130 said chambers and located at one side thereof to leave space at the other side thereof, there being an outer free and unobstructed annular air passage of relatively large cross sectional area, at the peripheral portion of 135 said space into which the air is deflected by said end tips of the fan blades, and a plurality of stationary vanes in the space between each fan and partition wall leading from said annular air passage to the open- 140

ing in the partition wall and forming separate air passages for the air discharged by the fan.

3. A compound turbine blower comprising a cylindrical casing having an air inlet opening and an air discharge opening and having a plurality of chambers separated by partition walls and connected by openings through said partition walls, a drive shaft and fans mounted thereon, the fan blades of which have end tips that are inclined with respect to the remainder of the blades, there being one fan in each of said chambers and located at one side thereof to leave a space 15 at the other side thereof, there being an outer free and unobstructed annular air passage of relatively large cross sectional area into which the air is deflected by said end tips of the fan blades, and there being stationary vanes in the space between each fan and partition wall leading from said annular space to the opening in the partition wall and other short stationary vanes located between said first mentioned 20 stationary vanes and leading from said annular air passage, said stationary vanes forming air passages for the air discharged by the fan.

4. A compound turbine blower comprising a cylindrical casing having an air inlet opening and an air discharge opening, and having a plurality of chambers separated by partition walls and connected by openings through said partition walls, a drive shaft and fans mounted thereon, the fan blades of which have end tips that are inclined with respect to the remainder of the blades, and there being one fan in each of said chambers and located at one side thereof to leave a space at the other side thereof, there being an outer free and unobstructed annular air passage of relatively large cross sectional area at the peripheral portion of said space into which the air is deflected by said end tips of the fan blades, and a plurality of stationary vanes in the space between said fans and partition wall extending in a tangential direction from said annular air passage to the opening in the partition wall and

forming separate air passages for the air discharged by the fan.

5. A compound turbine blower comprising a cylindrical casing having an air inlet opening and an air discharge opening, a plurality of partition walls in said casing dividing the same into a plurality of chambers connected by centrally located openings in the partitions, a drive shaft, fans mounted on said drive shaft and having blades forming air passages provided with air inlet 60 openings at their inner ends and discharge openings at their outer ends, the end tips of said blades being inclined with respect to the remainder thereof and each fan being located at one side of each chamber in the casing to leave a space in the other side of the fan and partition, there being an outer free and unobstructed annular air passage of relatively large cross sectional area at the peripheral portion of each space into 70 which air is deflected by said end tips of the fan blades, and stationary vanes in each of said spaces leading from each annular air passage to the opening in the adjacent partition.

6. In a blower, a cylindrical casing having a chamber provided with a centrally located air inlet opening and a centrally located air discharge opening, a drive shaft, a fan mounted on said drive shaft and having a plate dividing said chamber into two spaces, one of which is occupied by the fan, said fan having blades, the end tips of which are inclined with respect to the remaining portion of the blades, there being an outer 85 free and unobstructed annular air passage of relatively large cross sectional area at the peripheral portion of the space at the side of the fan and stationary straight vanes located in said space at the side of the fan, and 90 extending from said annular air passage in directions substantially tangential to the discharge opening of the chamber, said vanes forming air passages for conducting air discharged by the fan to the discharge opening.

EDWARD D. GREEN.
